UNITED STATES PATENT OFFICE

HEINRICH SCHÜNEMANN, OF SPANDAU, GERMANY, ASSIGNOR TO NEUER-BURG'SCHE VERWALTUNGSGESELLSCHAFT M. B. H., OF GEREONHAUS, COLOGNE, GERMANY, A CORPORATION OF GERMANY

MEANS FOR SPREADING CUT TOBACCO IN CIGARETTE-MAKING MACHINES

Application filed November 23, 1927, Serial No. 235,311, and in Germany September 10, 1925.

This invention relates to means for spreading cut tobacco in cigarette making machines, whereby it is possible to feed the cut tobacco from the container to the rod-forming mechanism of the cigarette machine in a layer of uniform thickness without tearing the fibres.

Various forms of the invention are shown on the drawing, in which:—

Fig. 1 is a diagrammatic section.

Fig. 2 is a perspective view of one form of the invention.

Fig. 3 is a diagrammatic section of a second form of the invention.

Fig. 4 is a diagrammatic section of a third form.

In accordance with the form of the invention shown in Figs. 1 and 2, the cut tobacco is supplied through a container 1, having guide surfaces and along a conveyor belt 2 to the circumference of a perforated rotating hollow cylinder 3, having an outer cover of wire cloth of fine mesh. Within this hollow cylinder is a second fixed cylinder on the circumference of which are arranged the guide rollers *c* which support the outer perforated cylinder 3. The interior of the cylinder 4 is kept clear by means of a pump, not shown. Arranged at a point opposite the inner end of the conveyor belt 2, the inner cylinder 4 is provided with a sector shaped channel *a*, the inner walls of which can be adjusted one with regard to the other and which is under the influence of a vacuum produced in the inner cylinder.

The tobacco carried by the belt 2 towards the cylinder body is drawn at *d* on to the rotating sieve cylinder 3, under the vacuum in the open part *a* *b* and is carried along as far as the point *b* at which point the suction effect of the vacuum in the hollow cylinder ceases, allowing the tobacco that has been carried along up to this point to fall uniformly on to a second belt 5. By means of the belt 5 the tobacco then reaches the usual forming chamber of the machine.

The guide rollers *c* also form a seal at the points *a* and *b* between the inner fixed cylinder and the outer rotating cylinder.

During the transfer of the tobacco from the wire clothed cylinder 3 to the conveyor belt

5 of the cigarette machine, by means of which the material is conveyed to the cigarette paper, an exact adjustment of the space subjected to the vacuum ensures the tobacco fibres being carried positively by means of the conveyor belt, which moves at right angles to the falling tobacco fibres, in the direction of the arrow. Owing to the fact that the suction on the tobacco fibres remains effective during this positive pull and that at the one end the tobacco fibres are not released until the last moment, a uniform deposit layer upon layer is assured of the tobacco fibres in the stratum and both as regards the thickness of the layer and the arrangement of the fibres longitudinally of the cigarettes to be subsequently formed. Owing to this pull and to the fact that the fibres thrown off are deposited in layers one over the other, any inequalities in length of the fibres are adjusted, thus leading to a thoroughly uniform composition of the layer.

In accordance with the modification shown in Fig. 3, a closed chamber 6 is provided to which the cut tobacco is fed through the inlet chute 8 by means of a belt 7. This closed chamber 6 is provided with a hood 9 which merges into a winnowing and discharging chamber 10. This discharging chamber 10 is provided with several discharge funnels 11, 12 and 13 arranged one behind the other and provided with discharge rollers 14, 15 and 16, which in accordance with the example previously described are formed as suction rollers, with suction of the air through the perforated jackets of the rollers and the hollow spindles thereof. Plates 14', 15', 16' are provided for breaking the vacuum on the lower adjustable portion of the jackets of the rollers for the purpose of delivering the sucked up layers of tobacco on to the conveyor belt 17 below. It will be seen that the suction of the air from the discharging rollers 14, 15 and 16 inside the casing 6 and the chamber 10 produces a current of air that is directed towards the rollers and by means of which the fed cut tobacco is drawn up and according to its length and weight is fed step by step to the rollers arranged one behind the other, so that the tobacco is deposited in lay-

ers on the conveyor belt 17, the heaviest layer being undermost, and on this the lighter layers are arranged so that a uniformly mixed layer or band of tobacco is formed 5 when the tobacco passes from the conveyor belt to the other mechanism.

A further advantage of the device is that the light tobacco fibres are to a certain extent dried by the current of air, and in addition 10 to this the drying process can be regulated by the speed of suction, the temperature selected and the degree of humidity in the in-drawn air. In order to break up any lumps that may form in the cut tobacco owing to its 15 lightness and thus to secure a more complete suction of the fed tobacco and uniform distribution in the current of air, a beater is fitted in the chamber 6 consisting of a vertical shaft 18 having vanes 19 arranged at 20 suitable intervals apart and which co-operate with other rigid vanes 20 provided within a perforated funnel 21 arranged in the chamber 6 and so break up the lumps of tobacco. At the same time, and owing to the effect of 25 the suction pipe 22, at the lower end of the chamber, light particles of dust contained in the tobacco are not carried off by the ascending current of air but are first carried away through the holes in the funnel 21, that is to 30 say, they cannot contaminate the layers of tobacco deposited on the conveyor belt 17.

The precipitating force of the rollers 14, 15 and 16 can if need be augmented by giving them an electrostatic charge. The 35 number of individual layers discharged by the rollers 14, 15 and 16 depends on the one hand upon the suctional power of the rollers and on the other hand upon their speed of rotation. Thus, any desired arrangement of 40 the layers of the tobacco fibres can be obtained by regulating the suctional power and the speed of rotation of the aforesaid rollers.

The further modification shown in Fig. 4 varies from that shown in Fig. 3 mainly in 45 the fact that the current of air which is employed to sift the cut tobacco is not produced, or not produced solely, by the suction rollers, but that an independent current of air is blown into the feed chamber for the cut 50 tobacco which draws up the tobacco and passes it on into the actual separating chamber in which the sifting is done according to the specific weight and the composition of the upper surface, whilst the very fine and 55 light fibres which are not drawn up are returned for further sifting.

In accordance with Fig. 4, 23 is the sifting chamber to which the cut tobacco is fed by the belt 24, and any lumps of tobacco that 60 may have formed are broken up into fibres by a rotating vane roller. Opening into the lower floor of the chamber 23 and supplied with air by a fan or a blower is a nozzle 26 through which the current of air is blown 65 into the pipe 27 which opens vertically into

the chamber. The fed tobacco falls on to the belt 28 and is drawn up by the current of air into the pipe 27. The pipe 27 merges into the horizontal pipe 29 which at its front end is open to the sifting chamber 30. The sifting chamber is provided with discharge openings 70 which are closed by means of discharge rollers 31, 32, 33, arranged one behind the other. The rollers 31, 32 and 33 are subjected to suction but can in addition to or in lieu thereof 75 be charged electrostatically, so that they deposit the sifted tobacco on the conveyor belt 34 according to the size of the fibre and the specific weight in the form of a band in successive layers and by means of which belt the 80 further feed to the cigarette machine is effected. The tobacco fibres not carried along arrive with the circulating air back into the chamber 23 and fall on to the conveyor belt 35 and from thence are blown into 85 the cycle by the current of air.

In the chamber 23, and for the returned fine tobacco fibres, can also be arranged a perforated partition wall 36 with a suction pipe 37 for the direct elimination of dust-like particles of tobacco and other dust contaminating the tobacco. In this way, whilst the very sensitive tobacco fibres are completely safeguarded, a uniform deposit of the cigarette tobacco is obtained in layers 95 with the elimination of the impurities and suitable drying for the most favourable treatment of the formed tobacco rod.

I claim:

1. A means for conveying cut tobacco and 100 depositing the tobacco so conveyed in a uniform layer on a travelling conveyor from a tobacco feeding means comprising a rotating hollow suction cylinder having spaced perforations and a fixed and hollow cylinder within said first cylinder provided with a sector-shaped suction opening in its outer periphery.

2. A means for conveying cut tobacco as 110 claimed in claim 1, and in combination therewith, of means for sealing the edges of said opening in the fixed cylinder and the inner periphery of the rotatable cylinder and to facilitate rotation of said rotatable cylinder on said fixed cylinder.

HEINRICH SCHÜNEMANN.
